UNITED STATES PATENT OFFICE.

JOSEPH GOGAN, OF CLEVELAND, OHIO.

FORMING AND TEMPERING APPARATUS.

Application filed October 18, 1926. Serial No. 142,233.

This invention relates to machines for forming and tempering metal plates and more particularly the leaves of rail or road vehicle springs and parts of vehicle bumpers.

5 It is one of the objects of the invention to provide a fluid operated mechanism that will be efficient and rapid in its operation and easy to control.

A further object is to provide an improved 10 forming and tempering machine that will be of simple construction and of low cost, as compared with machines heretofore used, and that will be reliable in its operation and durable and adapted to exert greater forming 15 pressure than prior machines of this class so as to make it possible to straighten the spring leaves edgewise and hold them against any tendency to work while cooling.

Other objects of the invention and the 20 features of novelty will be apparent from the following description taken in connection with the accompanying drawings, of which:

Fig. 1 is an elevation of a machine embodying my invention, certain parts being 25 shown in section;

Fig. 2 is a section on the line 2—2 of Fig. 1;

Fig. 3 is an enlarged section on lines 3—3 of Figs. 1 and 4;

30 Fig. 4 is a section on the line 4—4 of Fig. 3;

Fig. 5 is a detail section on the line 5—5 of Fig. 3;

Fig. 6 is a detail section on the line 6—6 35 of Fig. 3; and

Fig. 7 is a detail section showing the manually operable control valve in a different position from that in which it is shown in Fig. 1.

40 Referring to the drawings, 10 indicates a tank for a quenching or tempering fluid, this tank being preferably rectangular in shape and constructed of steel plates and structural steel members. Supports 11 and 45 12 are arranged on the bottom of the tank 10 and carry the columns 13 and 14, respectively. These columns are provided with vertical slots in their opposed sides to form the ways or guides 15.

50 A form-carrying member 16 is arranged in the tank 10 with its ends slidable between the ways 15. The member 16 carries one or more forms which may be of the usual solid type or may comprise a plurality of adjustable keys 17 on which the spring plate is

shaped, these keys being relatively positioned to give the desired curvature to the plate. Another form-carrying member 18 is arranged above the member 16 and has its ends slidable between the ways 15. The member 18 carries one or more forms that are complementary to the form or forms carried by the member 16, or the adjustable keys 19 which are arranged directly above the keys 17 and conform to the relative arrangement of the latter. The member 16 is provided with horizontally extending slots 20 to receive bolts 21 which are adapted to clamp the forms 17 in position, the forms being provided with vertical slots 22 to permit the necessary vertical adjustment of the forms. By this arrangement, the forms 17 are adjustable vertically and horizontally to suit the work to be treated.

The member 18 is, likewise, provided with 75 horizontal slots 23 to receive the bolts 24 by means of which the forms 19 are secured in position, these forms having vertical slots 25 which provide for vertical adjustment of the forms.

80 The upper portions of the columns 13 and 14 are bored out to form cylinders 26 in which the plungers or pistons 27 are adapted to reciprocate. Heads 28 are bolted on the upper ends of the columns 13 and 14 and each of these heads carries a cylinder 29 in which there is a plunger or piston 30 that is connected with the plungers 27, directly below, by a rod 31 which passes through the head 28. A pipe 32 connects with the lower 90 ends of the cylinders 29.

95 A pipe 33 connects with the upper ends of the cylinders 26. The plungers or pistons 27 are connected with the ends of the member 18 by connecting rods 34.

100 A manually operable control valve 35 is diagrammatically shown in the drawings as a four-way plug valve having an operating handle 36. The valve 35 is connected with the pipes 32 and 33 and also with a supply pipe 37 and a discharge pipe 38. The pipe 37 connects with a supply tank 39 and fluid under pressure, this fluid being preferably oil and being supplied to the tank 39 by a pump 40 which may be operated by an electric motor 41. A pipe 42 connects the pump 40 with the tank 39 and the pipe 37 communicates with the lower part of the tank, since it is desirable to have an air chamber in the upper part of the tank so that the tank will 110

act as an accumulator, in accordance with well known practice. The tank 43 serves as a sump to which the pressure fluid is ultimately returned and the pump 40 is connected with this sump by the pipe 44.

Arranged within the tank 10 are cylinders 45 having plungers 46, which are connected with the member 16 for the purpose of supporting and actuating the latter. A pipe 47 connects the lower ends of the cylinders 45 together, below the plungers 46; and this pipe 47 is connected with the pipe 32 by a pipe 48 in which there is a common check valve 49 adapted to permit the pressure fluid to flow downwardly through the pipe 48 but not upwardly. The pipe 47 also has connected therewith a pipe 50 which leads to the sump 43 and has an ordinary spring-held relief valve 51, which is adapted to permit the fluid to be discharged therethrough when the pressure in the pipe 47 exceeds a predetermined amount. Stops 52 are secured on the lower ends of the columns 13 and 14 to limit the downward movement of the member 16.

In the drawings, for convenience, the member 16 is shown at the lower limit of its movement and the member 18 at its upper limit but, when the member 16 is at its upper limit, the forms 17 are spaced far enough away from the forms 19 to permit the insertion and removal of the work, it being understood that in the actual operation of the machine the member 16 will always be at the upper limit when the forms are open. Assuming the member 16 is at the upper limit of its movement and held there, by the fluid in the cylinders 45, a piece of work is laid on the forms 17 and the valve 35 is positioned as shown in Fig. 1. This permits the fluid under pressure to flow from the pipe 37 to the pipe 33 and from the latter into the upper ends of the cylinders 26, above the plungers 27, thereby forcing the latter, and the member 18, downward against the work which is thereby clamped between the forms 17 and 19 and given its proper shape. The cylinders 45 are smaller than the cylinders 26 so that the forces acting on the plungers 27 will exceed the upward forces on the plungers 46. The member 18 will then force the member 16 downward, and the fluid in the cylinders 45 will be forced out through the relief valve 51 and return through the pipe 40 to the sump 43. When the member 16 engages with the stops 52, the downward movement of the members 16 and 18 will be arrested and the work will be submerged in the quenching fluid. The members 16 and 18 are allowed to remain in this position until the work has sufficiently cooled to retain its shape and then the valve 35 is adjusted to the position shown in Fig. 7. The fluid, under pressure, will then flow from the pipe 37 into the pipe

32 and from the latter into the lower ends of the cylinders 29, where it acts on the underside of the plungers 30 and causes these to rise and thereby lift the member 18 to its upper position. At the same time that the pressure fluid is flowing to the cylinders 29, it is also flowing through the pipe 48 and the check valve 49 to the cylinders 45 where it acts on the plungers 46 to lift the member 16 to its upper position. The forms 19 are thus disengaged from the work and the latter may be then removed from the forms 17 and a new piece put in position. The operations just described are then repeated.

It will be noted that, when the valve 35 is in the position shown in Fig. 1, the pipe 32 is placed into communication with the discharge pipe 38 so that the fluid may be discharged from the cylinders 29 as the member 18 moves downward. When the valve 35 is in the position shown in Fig. 7, the pipe 33 is in communication with the discharge pipe 38 so that the fluid may be discharged from the cylinders 26. The check valve 49 prevents upward flow of the fluid through the pipe 48 and thus serves to maintain the pressure in the cylinders 45 even though the pipe 48 is in communication with the discharge pipe 38, as shown in Fig. 1.

Having thus described my invention, what I claim is:

1. In a machine of the class described, the combination of guiding means, a form-supporting member movable on said guiding means, fluid pressure means for moving said member in one direction, a second form-supporting member reciprocable toward and away from the first-mentioned member and cooperating therewith to clamp the work, and fluid pressure means for actuating said second member having sufficient power to move both of said members in one direction and in opposition to the force exerted on the first member by its said fluid pressure means.

2. In a machine of the class described, the combination of guiding means, a form-supporting member movable on said guiding means, fluid pressure means for moving said member in one direction, a second form-supporting member reciprocable toward and away from the first-mentioned member and cooperating therewith to clamp the work, fluid pressure means for actuating said second member having sufficient power to move both of said members in one direction and in opposition to the force exerted on the first member by its said fluid pressure means, a system of pipes for supplying fluid under pressure to both of said fluid pressure means and including a manually operable valve for controlling the flow of fluid to both and the discharge of fluid from one of said fluid

pressure means, and an automatically operating valve for controlling the discharge of fluid from the other of said means.

3. In a machine of the class described, the combination of a tank for quenching fluid, a pair of spaced guides in fixed relation to said tank, a form-supporting member movable on said guides into the fluid in said tank, a pair of cylinders located in said tank and having plungers which support said member, a second form-carrying member movable on said guides above the first member, fixed cylinders having plungers connected with said second member to move the latter toward and away from said first member, pipes connected with all of said cylinders, a manually operable valve for controlling the supply of fluid under pressure to all of said cylinders, and an automati-

cally operating valve for controlling the discharge of fluid from the first-mentioned cylinders when said members are forced down into the quenching fluid.

4. In a machine of the class described, the combination of a tank for quenching fluid, a pair of upright columns provided with ways, form-carrying members slidably arranged one above the other on said ways, means for raising the lower of said members, cylinders carried by said columns, plungers movable in said cylinders, connecting rods forming an operative connection between said plungers and the upper of said members, and means for supplying fluid under pressure to said cylinders to actuate said plungers.

In testimony whereof I affix my signature.
JOSEPH GOGAN.
